GARMENT POCKET ASSEMBLAGE

William Landy, Cleveland, Ohio

Application August 25, 1948, Serial No. 46,053

4 Claims. (Cl. 2—253)

1

This invention relates to improvements in garment pocket assemblages.

Male garments, for which the present invention is especially designed, are provided with pockets with the locations practically fixed according to standards of long usage and similarly the forms of the different pockets have been more or less standardized. The present invention does not materially change these conditions.

It has also been proposed to add additional pockets as auxiliary to the standard pockets. For instance, it has been contemplated to provide an additional pocket effect in connection with a standard pocket, as by dividing the latter, or by the addition of a second pocket within the standard pocket, with the latter generally formed to be removable at will. With the former (exemplified by the small change pocket within one of the coat pockets) both pockets are open for service at all times, while with the latter, the added pocket may serve to provide the service of the standard pocket, as where the standard pocket has become worn and the removable pocket is then positioned therein to perform the service of the standard pocket, it then being possible to substitute one removable pocket for another to meet the conditions of wear of the pocket being substituted.

The present invention is of the dual pocket type, but differs from the types referred to in that under normal service conditions only the additional pocket is open for usual service, but having the standard pocket completely serviceable and accessible at will. This practically makes the standard pocket more or less of the secret pocket type. For instance, the added open-mouth pocket may be used for carrying usual articles, including monetary change, with the standard pocket used for carrying paper money or the like and the assemblage permits temporary separation of a side of the added pocket from its connection with the standard pocket thus affording access to the secret standard pocket. While the removable pocket referred to above (generally secured in position by buttons or snap fasteners) will permit such opening at the side of the standard pocket, the arrangement necessarily discloses the presence of both pockets, thus destroying the secrecy characteristic of the standard pocket, since the division of the walls

2

of the two pockets, due to the nature of the mounting, is apparent even to casual inspection and feel.

In the present invention, the mounting is such as to make the added pocket either a permanent part of the assemblage or it is possible to remove the added pocket by temporarily deranging the closed end of the mechanical fastening which is utilized. This would permit of the substitution of a new pocket by then incorporating the latter with the connection and restoring the end closure conditions. However, the invention is not restricted to providing the removable effect, the purpose being rather to provide an assemblage of the standard and auxiliary pockets as a definite standard and capable of being produced at the time the garment is being made regardless of whether or not the auxiliary pocket is fashioned for removal.

20 The assemblage preferably makes use of the "zipper" form of mechanical fastening in the mounting of the auxiliary pocket. This form, when the zipper is closed, provides an approximately smooth face such as can form a definite part of the pocket wall without affecting the free movement of the hand into and out of the pocket. With a button or snap fastening, there is present a superposed ply over the standard pocket ply so that the hand can readily pass between the plies and reach into the standard pocket, but with the zipper type, access to the standard pocket could be had only by actuating a zipper slide. This difference in action is advantageous as a preventative of pick-pocket activity designed to reach the secret standard pocket, since attempted movement of the slide would be instantly detected. With the zipper segment-carrying side strips permanently sewed to the exposed face of the wall of the standard pocket and to the outer face of the auxiliary pocket, the inner face of the zipper formation is maintained smooth, excepting when the slide is actuated to open the mouth of the standard pocket.

45 The assemblage is particularly applicable for use with male garments, and especially with the side pockets of trousers, although it is applicable for use in connection with coat pockets where the garment is designed for special services. Its great value comes in connection with its service

with one or both of the side pockets of the trousers, since these generally carry money values and the presence of a secret and protected pocket can serve to carry "paper money" with less danger of loss and in a position more difficult to surreptitiously abstract, due to its location.

To these and other ends, therefore, the nature of which will be better understood as the invention is hereinafter disclosed, said invention consists in the assemblage formations hereinafter fully described, illustrated in the accompanying drawings, and more particularly pointed out in the appended claims.

In the accompanying drawings, in which similar reference characters indicate similar parts in each of the views:

Figure 1 is a fragmentary side elevation of a pocket zone of a trousers assembly showing the present invention in applied position, parts being broken away to illustrate underlying parts, entrance to the standard pocket being concealed.

Fig. 11 is a fragmentary view, in elevation of the closed end zone of an alternative form of zipper formation for service in connection with removable pockets.

Fig. 12 is a vertical sectional view, the plane of section being central of the anchoring member and parallel with its face.

Fig. 13 is a similar view showing one of the segment-bearing strips in detached position.

Fig. 14 is a schematic elevation of the zipper formation, with parts broken away, and showing an overlying fabric cover for the segment zone.

Fig. 15 is a sectional view taken on line 15—15 of Fig. 14.

The assemblage is made up of a standard or conventional pocket, which forms a part of the garment, an auxiliary pocket dimensioned for mounting within the standard pocket, and a mechanical fastening structure of the zipper type connecting the mouth zones of the two pockets on opposite sides of the auxiliary pocket, thus making possible the opening of the standard pocket on either side of the auxiliary pocket.

This is made possible by securing, as by sewing, the side strips of the zipper formation which carry the zipper segments, respectively to the inner face of the mouth of the standard pocket and to the outer face of the auxiliary pocket, with a separate formation used for each of the opposite sides of the mouth of the auxiliary pocket. The dimensions of the mouth zone of

the auxiliary pocket can thus practically conform to those of the mouth zone of the standard pocket, or can be varied therefrom to make a different mouth for the auxiliary pocket by the arrangement of the zipper formations. By extending the length of movement of the zipper slide to equal the length of a lip of the mouth of the standard pocket at each side of the latter, the mouth of the auxiliary pocket practically becomes a substitute for the mouth of the standard pocket leaving the entrance to the standard pocket wholly concealed. If the slide on but one side is moved to open position, access to the standard pocket is opened through the open side; if both slides are moved to open position, the mouth of the auxiliary pocket can be collapsed into position at the closed end of the formations, thus practically opening the mouth of the standard pocket to almost complete extent.

If the length of slide movement is made less than the length of the adjacent lip of the auxiliary pocket, as by locating the closed position of the slide below the upper end of the lip of the mouth of the auxiliary pocket (assuming use in a side trousers pocket) the unsecured portions of the lips can be in the form of a free zone of the mouth of the auxiliary pocket. Such zone is capable of folding into position conforming to the mouth of the standard pocket or provide an opening of greater width in the upper zone of the auxiliary pocket when entrance into the pocket is being had. The free zone being at the top of the pocket would be free to assume either condition, since the support of the pocket content is provided by the connected portions of the sides. The complete physical concealment of the standard pocket is changed by such arrangement, since the entrance of the hand into the auxiliary pocket would cause the free zone to change its form and expose a small portion of the upper end of the standard pocket. However, the exposed zone would not permit the entrance of a hand therethrough to gain access to the lower zone of the standard pocket unless at least one of the slides was moved to its open position. The arrangement thus provides ample protection against pocket-picking of the standard pocket, even though the entrance to the standard pocket is not completely concealed and closed.

As will be understood, the auxiliary pocket is permanently open, the zipper formations anchor such pocket to the standard pocket, but have no effect upon the mouth of the auxiliary pocket. The zipper formations conceal, or nearly conceal, the interior of the standard pocket and prevent entrance thereto when the slides are in closed position. The movement of a slide to open position is always in the direction of length of a lip of the mouth of either pocket, and only by such movement can the content of the standard pocket be reached. Since such direction of slide movement is transverse to the distance between the lips of the mouth, and the slide movement in itself does not materially increase such distance, actual entrance of a hand to gain access to the standard pocket content requires the initial slide movement to prepare the mouth to receive the hand, and since the direction of slide movement is transverse to the direction of movement of the hand in making the entrance, the two activities are necessarily successive and cannot be concurrent. Because of this, any attempt at pocket-picking with respect to the standard pocket, is made exceedingly difficult and liable to detection through the movements required to

open the zipper slide and the need for the succeeding entrance of the hand.

In Figures 1 to 7, the assemblage is shown as applied to a side pocket of a pair of trousers. In these figures, A indicates a portion of the trousers, and B the standard pocket thereof having the mouth zone *b* the outer side of which is the usual outer side of the mouth of the pocket zone, the opposite side of the pocket generally extending to the side seam of the trousers, A' indicating a usual facing of trouser material which is exposed at the entrance to the inner side of the conventional pocket.

The auxiliary pocket is indicated at 10, and is shown illustratively, since it may have any desired conformation which would be conveniently received within the standard pocket. The pocket 10, however, has its mouth 11 dimensioned with respect to the dimensions of the mouth zone *b* as above explained. Any desired material can be used in the production of the auxiliary pocket. For instance, it can be of fabric type similar to the standard pocket, or may be formed of chamois or the like, or it may be formed of soft leather, the material used being dependent somewhat upon the particular service to which the pocket is to be put.

The two lips 12 of the mouth 11 are secured to the lips of mouth *b* by the use of mechanical fastening formations of the zipper type, one formation for each of the lips of the respective mouths, these formations being generally of standard type made up of segment-bearing strips 13, with the segments of the closed end of the formation united by a suitable member 14, the formation including a slide 15 which is designed to move between the opposite end zones of the opposed segment series to place the formation in either its closed or open positions. The member 14 serves normally to anchor the segment-bearing strips together at the closed end, and is generally not designed for removability without disrupting the formation.

As shown in Fig. 2, when applying the pair of formations to complete the assemblage, the proper strip 13 of one formation is applied to the inner or exposed face of the outer or loose ply of the standard pocket (shown as the lower side of the standard pocket in this figure) the edge of the strip may be infolded as shown. The other strip 13 of the formation is secured to the outer or concealed side of the mouth ply of the auxiliary pocket, the strips being secured to the respective plies by stitching lengthwise of the strips, so that the latter become permanent parts of the mouth zones of the standard and auxiliary pockets. The application of a similar formation to the opposite side of the standard pocket may be similar to the above, or applied between the facing strip A' and the face of the standard pocket, if the facing strip be formed of trouser material (the arrangement shown as the upper side of the standard pocket in this figure), in which case the facing strip may extend to and into the side seam of the trouser.

In mounting the formations, the length of the strips 13 may be such as to extend for the full length of the loose ply of the standard pocket and the full length of one of the sides of the mouth zone of the auxiliary pocket, in which case the segment zone would extend from the top to the bottom of the mouth of both pockets. In such case, the ends of the respective strips 13 of the two formations would be practically joined at the top and bottom portions of the mouths of

both pockets. If the arrangement is such that both slides move in the same general direction in moving between open and closed positions, both slides would normally be located at the same end in closed position, preferably the top of the mouth, since in such position the slides would not interfere with the entrance of the hand into the auxiliary pocket.

As shown in Fig. 6, the length of the strips 10 may be made less than the length of the lips of the mouth of the auxiliary pocket, in which case the strips 13 extend to the bottom of the mouth zone of the auxiliary pocket but terminate short of the upper end, the slides thus being located, in closed position, spaced from such upper end thus leaving a free and unsecured zone of the auxiliary pocket between the slides in such position. As explained above, this permits of a greater width at the top of the mouth of the auxiliary pocket for the entrance of the hand, but leaves the standard pocket as exposable within this free zone, although the normal folding of the free zone would nominally also close this zone of the standard pocket, thus distinguishing from the other form in which the entrance to the standard pocket is practically concealed by the fact that its mouth is closed by the two zipper formations, the strips 13 of which are secured, by sewing, to the respective lips of the mouth zones of both pockets and the even face of the zipper segments interlocked by the movement of the slides to the closing position.

However, the Fig. 6 form of pocket also permits of the use of the pocket where the standard pocket formation tends more to the "slash pocket" effect, the free side of the pocket extending angular to the vertical. In such form, the strip length shown is of the full length of such free side, the horizontal portion of the pocket shown in Fig. 6 being designed to overlie the trouser zone between the top of such free side and the opposite zipper formation location, a zone which is normally exposed. Since this zone is on the side of the trousers and follows the curvature of the body, such horizontal portion will be held in contact with the trouser material, and need not be stitched to the material. It is a form especially adapted for service under the removable pocket conditions presently referred to.

As is evidenced from Figs. 1 to 7, the auxiliary pocket is supported in position entirely through the zipper connection between the pockets. This permits the removability of the auxiliary pocket referred to. Under these conditions, the angular inclination of the entrance to the auxiliary pocket provided by the slash pocket effect is of especial importance. This can be understood from the fact that with an entrance that is truly vertical, the zipper formations would extend truly vertical with the stitching line being practically linear in such direction. Under such conditions, the pocket support would be limited to such direction and of practically linear width. By extending the entrance angularly inclined forwardly 65 from its lower end upward to the top, the sewing line remains linear in type, but the pocket support effect takes on the character of a band of considerable width, since the progression of stitches, although linear, are laterally displaced slightly relative to each other and with respect to the true vertical, and each stitch thus becomes the equivalent of a separate supporting connection for the pocket, thus setting up a band effect having a width equal to the width of the angle, 70 it being understood, of course, that a supporting

effect is present with each stitch although the progression of stitches may place the support effect of one stitch as located a different distance from the top of the pocket as compared with another stitch, each stitch thus tending to produce an individual support, as compared with a common supporting effect produced where the stitching is truly vertical. With the stitches thus distributed to produce the band like effect, the auxiliary pocket becomes adequately supported and positioned within the standard pocket.

While it is preferred to locate the zipper formations in such relation that the slides are in their upper positions when the formation is in its closed condition, it is apparent that this may be reversed so that the closed positions would have the slides at the bottom, or the arrangement could be such that the slide of one formation is at the top and the other at the bottom, when both are in closed position, the latter arrangement obviously preventing any confusion in the selection of slide to be moved when it is desired to open up a side of the standard pocket to permit entrance thereto. The slide formation is of such form that either condition can be secured by the needed arrangement of strips 13 at the time the formations are being installed to connect the two pockets.

As will be understood, the fact that the zipper formation is itself an assemblage which presents its opposite faces as practically flat, serves to make the assemblage of the invention one that is not only readily applied in position, but which permits the use of the auxiliary and permanently open pocket with minimum interference to the entrance of the hand, even though the zipper formation be exposed beyond the lips of such pocket. This is due to the fact that the under side of the formation, being substantially flat, lies in close contact with the face of the standard pocket, while the exposed face, also flat when the zipper slide is in closed position, presents no material irregularities such as could injure or interrupt the free entrance of the hand. Actually, the user scarcely notices the presence of the narrow metallic strip-like body which the segments produce, as the hand approaches the actual lips of the pocket. And while the actual lips of the pocket are exposed on the inside of the entrance, the fact that the lip and the strip 13 are secured together by sewing throughout the length of the strip prevents the exposed lip from producing any obstructive effect to the entrance of the hand into the pocket.

As indicated in Figs. 14 and 15, the exposed faces of the segments of the zipper may have a fabric cover 25, this being sewed to the strip 13 with a loose portion overlying the segments and which lies within the slide, thus permitting free slide movement over the cover with the segments covered. When this form is used, the segments are unexposed at the entrance to the auxiliary pocket, the exposed surface of the zone being of fabric type.

When a slide is moved to open the formation (Fig. 4), the entrance to the standard pocket is thereby opened with the separated segments forming the side edges of the opening; while the segments are individual, they are small and present no material sharp edges, the adjacent prongs being close together, so that the hand can be introduced through the created opening with freedom and with practically no liability of being damaged by the side walls which are open.

Due to the fact that the segments are individ-

ual and small, the zipper formation is flexible in the direction of its length so that the opposing closed zipper formations which are located adjacent the lips of the auxiliary pocket readily conform to the shape and the dimensions of the hand being introduced into or withdrawn from such pocket. The same is true when access is gained to the standard pocket by moving one of the slides to open the formation, since the flexibility of the segments remains and the walls of the auxiliary pocket are themselves of flexible material.

As shown in Figs. 8 to 10, the invention is also readily applied to the pockets of coats. Since the lips of such pockets generally extend horizontally, the direction of length of the zipper formations extends in the same direction. And with such pockets it is possible to locate the lips of the auxiliary pocket somewhat below the lip zone of the standard pocket, if desired, since the mouth zone of the standard pocket, which includes the opposite zipper formations, will in effect form a portion of the auxiliary pocket by serving as the entrance to the latter.

The auxiliary pocket may be removable or not removable, as desired, this depending upon the character of the zipper formation that is being employed. For instance, with the usual commercial form of zipper formations, one end zone is generally formed in such way as to hold the end segments of the zone anchored in locked position by member 14, the slide moving toward and from such member when opening and closing the formation. Due to the anchored condition of member 14, the two segment-bearing strips are not separable bodily, excepting by deranging or disabling member 14. Under these conditions the auxiliary pocket would be considered as of the non-removable type, since it would be necessary to derange or disable member 14 to permit separation of the strips 13. The member 14 may be deranged or disabled and thus permit separation of the strips, and thereby change the auxiliary pocket into a pocket of the removable type, but when the strips 13 are again assembled, a new member 14 would probably be required, owing to the difficulty of restoring the disabled member to its original form.

However, as shown in Figs. 11 to 13, the zipper formation may have its closed end zone of special formation. In the form shown, the assemblage normally functions in service similar to the commercial form referred to. However, when it is desired to bodily separate the strips, the end of at least one of the segment-bearing strips is bodily removed from the member to break down the normal relation therebetween; preferably the member is so arranged as to limit the withdrawal to but one of the strips, so that when the separation is had the member will remain with the other strip. The co-relation is such that by simply restoring the strip to the member after restoring the slide relation, the formation becomes restored to normal condition. With such arrangement, the auxiliary pocket is removable at will.

In the formation shown in these latter figures, the anchoring member, indicated as 20, is formed with two parallel zones extending longitudinally, the zones being connected medially with rounded surfaces. One of the zones is solid and formed with a pin-like extension 21 to which the end segment of one of the strips 13 is permanently secured, thus anchoring the member to such strip. The other zone is recessed inwardly from

its upper end adapted to receive the end of a pin 22 which is carried by the lower segment of the other strip 13; when pin 22 is properly positioned within the recess, the exposed portion of the pin forms the equivalent of pin 21, thereby placing the lower segments of the two strips as properly positioned for zipper action by slide movement.

When pin 22 is withdrawn from its recess, the normally closed end zones of the zipper formation become separated, making it possible to withdraw the strip 13 which bears pin 22 from the slide, thus completely separating the two strips, with the slide and member 20 remaining on the strip which carries the pin-like member 21. By again threading the withdrawn strip through the slide and then positioning pin 22 within its recess, the zipper formation becomes restored to its normal condition.

The arrangement permits removal of the auxiliary pocket at will, when the formations on each side of the pocket have both been manipulated in such manner as to separate the two strips of a formation, and whether the removed strip is carried by the standard pocket or by the auxiliary pocket. Obviously, a substitute auxiliary pocket may be equipped with the strips 13 of the removed pocket or with an equivalent strip on each side, and can be properly positioned in the standard pocket by following the above indicated manipulations. When the zipper formation is restored, the member 20 with its pin 21 and the positioned pin 22 provide the closed end of the formation with the slide operative to open and close the formation in normal manner.

Since the auxiliary pocket, with its permanently open entrance, forms the primary service pocket of the assemblage, and is thus subject to the greatest wear, this ability to bodily remove the pocket by simple manipulation of the zipper formations, enables this pocket to be renewed at will or enables the substitution of a particular type of service pocket designed to meet special conditions, such, for instance, as the substitution of a leather pocket for one of woven fabric material, whenever it is desired to make such substitution. Where the strips 13 of the removed pocket are used with the substitute, the substitution involves only the temporary separation of the strips 13 of the pair of formations and the return thereof to normal service conditions. Obviously, the form and dimensions of the substituted pocket may be varied as desired, as long as the entrance dimensions accord with those of the removed pocket.

While the zipper formations have heretofore been utilized for closing the lips of a pocket and have been used as a ready means for controlling the opening and closing of garment openings, its use in the present invention differs somewhat from the usual manner of use in these services, in that the formation itself becomes a definite and important element of the entrance to the auxiliary pocket, forming part of the walls of such entrance with the pocket itself remaining permanently open, thus augmenting the usual service usage of such formations. Because of this condition, the character and position of the zipper formation together with its manner of mounting becomes of definite importance, since it must permit the free entrance of the hand into the auxiliary pocket.

While I have herein shown and described several ways in which the invention may be utilized, it will be understood that changes and/or modi-

fications thereof may be found essential or desirable in meeting the exigencies of service or the individual desires of a user; I, therefore, reserve the right to make any and all such changes and/or modifications therein as may be so found essential or desirable, insofar as the same may fall within the spirit and scope of the invention as expressed in the accompanying claims, when broadly construed.

What I claim is:

1. A pocket assemblage for the side pockets of trousers comprising a standard or conventional pocket formation wherein the entrance is elongated approximately vertically and its length is less than the depth dimension of the pocket, an auxiliary pocket also having an elongated entrance the length of which is less than the pocket depth, the direction of entrance elongation being angularly inclined forwardly to the vertical from its lower end to its top zone, and means for mounting the auxiliary pocket relative to and within the standard pocket with the respective entrances or mouths substantially aligned and with the means operative to maintain the positioned auxiliary pocket entrance permanently open and active to substantially conceal entrance to the standard pocket, said means including a normally closed zipper formation connecting a side wall of the entrance of the standard pocket with a similar wall of the entrance to the auxiliary pocket, and a similar zipper formation connecting the side walls of the two pockets at the opposite side of the entrances, said zipper formations providing the supporting means for the positioned auxiliary pocket with the pockets otherwise free from mutual securing connection, said zipper formations when closed preventing access to the standard pocket through its entrance, the movement of the slide of either zipper formation to open position being operative to open the corresponding side of the entrance of and permit access to such side of the interior of the standard pocket.

2. An assemblage as in claim 1 characterized in that the zipper formation has its segments carried by fabric strips, the securing of the formation in position being by a sewed connection between the strips and the respective pocket mouth zones to thereby position the slide direction of movement between open and closed positions as being outside of the lips of the mouth of the auxiliary pocket, and further characterized in that one of the segment-bearing strips of a zipper formation is sewed to the exposed face of the mouth of the standard pocket with the strip of the opposite and complementary member of the formation sewed to the concealed side of the auxiliary pocket.

3. An assemblage as in claim 1 characterized in that the length of each zipper formation extends from one end of the lip zone of the mouth of the auxiliary pocket to a point at least approaching the opposite end of such lip, with the closed position of the slides of both formations located at such latter point.

4. An assemblage as in claim 1 characterized in that each zipper formation includes a member operative to maintain an end zone of the segment bearing strips in anchored closed relation in service, the lower segment of at least one of the strips being separable from said member to thereby permit separation of the strips of each zipper formation and permit bodily removal of the auxiliary pocket at will, such end segment carrying a pin adapted to be removably mounted

11

within the member and in position to render the end segment cooperative with the end segment of the companion strip for zipper functioning.
